[57] CLAIM

The ornamental design for a corner connector for furniture panels, as shown and described.

DESCRIPTION

FIG. 1 is a perspective view of a corner connector for furniture panels showing our design, the broken line depiction of furniture panels being shown for illustrative purposes only;

FIG. 2 is an exploded view showing the connector on an enlarged scale and rotated counter clockwise to illustrate the features thereof in greater detail;

FIG. 3 is an elevational view showing the outer surface of the connector with the end cap omitted and portions omitted for convenience of illustration; and

FIG. 4 is an elevational view similar to FIG. 3 but showing the inner surface of the connector.
